TELEPHONE SWITCH OR TELEPHONE
CONTACTGeorge H. McLoughlin, Scranton, Pa., assignor
to Automatic Electric Laboratories, Inc., Chi-
cago, Ill., a corporation of Delaware

Application December 9, 1940, Serial No. 369,157

1 Claim. (Cl. 179—159)

This invention relates to electric switches, contacts or buttons used on telephone sets consisting of a sound receiver and transmitter and suitable stands, bases, hangers, holders or cradles for holding same; and the primary object thereof is to provide a magnetically operated telephone switch for the purpose of breaking and closing an electrical telephone circuit and for the purpose of providing an entirely enclosed switch so that said switch cannot be accidentally or deliberately operated while the telephone is in use and to prevent dust and other material from reaching the switch and interfering with its operation and to prevent sparks created by the switch from igniting any gases present in the surrounding atmosphere; and to this end my invention consists of movable permanent magnets which normally attract or repel magnet arms (attraction or repulsion depending upon the arrangement of magnetic poles), thereby breaking the circuit, and when the movable magnets are removed they no longer influence the magnet arms and these arms are retracted by springs to make electrical contact and thus complete the telephone circuit.

It also consists of magnets arranged in the handpiece in such a way that two of their similar magnetic poles are farthest from each other, thus a similar pole will always be in the proper place above the arm regardless of which way the handpiece is placed in the cradle.

Also, it further consists of novel combinations, arrangements and relation of parts, which are revealed in the description.

Two similar switch units are shown in each phone of each drawing in order to illustrate a useful method of utilizing this magnetic switch.

The drawing is a front elevation in detail of a telephone handset cut away to show the application of my invention. The drawing shows the switch open and the circuit broken.

In the drawing, for the purpose of illustration and revelation is shown one method of constructing and applying the invention to telephones.

The drawing shows a switch operated by magnetic repulsion. The views of the drawing are as follows:

Fig. 1. A telephone handpiece including receiver and transmitter and showing magnets set in the handpiece.

Fig. 2. The telephone base containing the contact parts of the switches.

Fig. 3. A part of the switch (the magnet arm) showing the method of attaching the magnet or magnetic metal piece to the axle and stand, and

also the method of insulating the contact spring from the arm.

The numerals designate the parts which are described in the following paragraph:

5 In drawing number one—numeral 1 designates the permanent magnets set in recesses in the handpiece 22, and attached by means of bolts 15 and surrounded by the phone casing 16, and having their north poles 24 at the farthest distance 10 from each other. Numeral 2 designates the magnet arms which are held by the magnet grips 5, provided with holes 29, through which pass axles 23 set in axle stands 6 which are attached to the base casing 17 by means of nuts 8. Numeral 3 15 designates a pair of springs which are held in place by bolts and nuts 7 and which press upwardly on arms 2. Numerals 9, 10 and 12 designate electric wires, which provide an electric circuit through upwardly making contact point bolts 11 and contact springs 4 which are attached to arms 2 by means of bolts 28 and insulated from arms 2 by means of insulating washers 27 and 26. Numeral 25 designates the north poles of the magnet arms 2; thus numerals 24 and 25 20 25 designate like magnetic poles in combinations of magnets which are like in any pole relations or arrangements. Numerals 21 and 20 designate hollow spaces of base. Numeral 19 designates the phone cradle which is attached to the removable 30 top 18, which is attached to the base casing 17 by means of bolts 14. Numeral 13 designates the telephone cable containing wires leading to the switch.

The operation is as follows: When the handpiece 22 is in the cradle 19, the magnets 1 and magnet arms 2 repulse each other and thus the pivoted magnet arms 2 are forced or repulsed by magnetic repulsion of like magnetic poles, thereby withdrawing the contact springs 4 from engagement with the extended contact point bolts 11 and thus breaking the circuit, this being the normal disposition of the parts as long as the handpiece 22 remains in the cradle 19. When the handpiece 22 is removed from the cradle 19, the mutual magnetic influence no longer exists, leaving the arms 2 free to be raised by the springs 3 and thus causing the contact springs 4 to engage the extended contact point bolts 11 and close the circuit, thus allowing the passage of an electric current through the telephone circuit.

I am aware that prior to my invention some types of magnetically operated switches have been made. I, therefore, do not claim the magnetically operated switch in its entirety, but only

those types and applications stated in the following.

I claim:

A telephone switch system comprising two or more sets of magnets arranged to act in unity and consisting of a plurality of magnets movably mounted within a desk set, in combination with a plurality of magnets immovably mounted on a hand set, said magnets having their like poles so arranged that one set of like poles are adjacent each other while the other set of like poles are remote from each other and also being so ar-

ranged as to establish magnetic repulsion forces between said desk set magnets and said hand set magnets when the hand set is supported in any position on the desk set, electrical contact points 5 arranged to cooperate with said desk set magnets, said repulsion forces causing a united displacement of all desk set magnets to hold open said electrical contact points, spring means urging said contact points into contact, whereby the circuit through the desk set is completed only when the hand set is removed from the desk set.

GEORGE H. McLOUGHLIN.
